RACE COURSE CONSTRUCTION

Filed Dec. 1, 1926

FIG. - 1

FIG. - 2

FIG. - 3

Inventor

John F. Jennings

By, Bette Macklin, Solitude, Pearce

Attorney

UNITED STATES PATENT OFFICE.

JOHN F. JENNINGS, OF CLEVELAND, OHIO.

RACE-COURSE CONSTRUCTION.

Application filed December 1, 1926. Serial No. 151,883.

The customary construction of a race course includes a home and a back stretch with connecting curves, and an inside boundary line which extends along the 5 stretches tangentially to the curved portions. During a race the constant effort of the contestants to gain the "pole" is particularly noticeable at the beginning of the stretches where the majority of accidents, especially 10 in horse racing, occur.

The principal object of the present invention is to construct a race course which permits maneuvering of the contestants at the 15 beginning of the stretches with less danger than on present forms of courses. Moreover my invention contemplates an improved race course construction which may be adapted to present courses without materially changing the construction of the same.

20 My invention is shown as applied to both the home and back stretches in Figs. 1 and 3, while Fig. 2 shows the application only to the home stretch; Fig. 3 moreover shows the 25 relationship between the old and new forms of race course construction.

I have indicated a race course embodying my invention as embodying a trackway having an inner boundary 10 and an outer boundary 11. The trackway has a home and 30 back stretch, the ends of which are connected by curves 14 and 15 respectively. As shown in Fig. 1 the inner boundary has a straight portion 16 which near the beginning of the home stretch is offset from the inner boundary 17 of the curve 14, while the end of the 35 home stretch extends tangentially to the inner boundary 18 of the curve 15. Similarly the straight portion 19 on the inner boundary of the back stretch is offset near 40 the beginning of the stretch from the curve 18, but at the end of the stretch is disposed tangentially to the curve 17. This offset 45 relationship of the straight and curved portions of the inner boundary is illustrated in Fig. 1 as being on both the home and back stretches, but in Fig. 2 it is shown only on the home stretch.

By making the inner boundary of the 50 stretches offset with relation to the end of one of the curves, I provide an additional track area, which may be used for enabling one contestant to pass another on the inside, and thereby eliminating, to a great extent, the dangers incident to the maneuvers of 55 competitors at the beginning of the stretch. By providing a track rule that any con-

testant who has the "pole" at the end of the curve, must proceed in a straight line down the stretch, then the following contestant who may be "boxed in" at the curve can 60 pass the former "pole" holder on the inside while on the stretch. This not only tends to minimize accidents, but also tends to speed up a race.

In adapting my invention to present forms 65 of race courses, I show in Fig. 3 my improved form of course in full lines and the present form of course in dotted lines. To employ my invention, it is only necessary to extend the end of the curve outwardly 70 beyond the normal line 22 and then to connect the end of the curved boundary to the present boundary for the straight away portion by an obliquely extending portion, as at 20 and 21, respectively. If desired this 75 connecting portion may extend at right angles to the boundary of the straight away portion, but this is optional so long as a material offset to the inner boundary is provided. To compensate for the increased 80 distance around the track, the shape of the boundary 23 at the beginning of each curve may be modified to a slight extent. This modification will only require the construction of a relatively small proportion of new 85 track area at the beginning of the curves.

By means of my invention, new race 90 courses may be constructed at substantially the same cost as the present form of course, while existing courses may be readily modified in an inexpensive manner. My invention is useful in that it minimizes the danger 95 incident to the operation of race courses.

I claim:

1. A race course having curves and connecting stretches, there being an inward offset on the inner boundary of one of the stretches.

2. A race course having curves and connecting stretches, and having the inner 100 boundary of at least one of the stretches offset inwardly from a tangent to the end of the inner boundary of one of the curves.

3. A race course having an inner boundary comprising curves and straight portions, at 105 least one of the straight portions on the inner boundary extending tangentially to the beginning of one of the curves at one end of the track, and being offset from a tangent to the end of the curve at the opposite end 110 of the track.

4. A race course having an inner boundary

comprising curved portions at the ends of the trackway and straight line connecting portions, the beginning of at least one of the straight line portions being offset inwardly from a tangent to the end of an adjacent curved portion.

5. A race course having an inner boundary comprising curves, and straight portions, at least one of the straight portions extending

tangentially to the beginning of one of the curves at one end of the track and having a portion extending obliquely from a tangent to the end of the curve at the opposite end of the track.

In testimony whereof, I hereunto affix my signature.

JOHN F. JENNINGS.
